FOREIGN PATENT DOCUMENTS

EM 002650416-0038 * 3/2015

Primary Examiner — Paula Allen Greene(74) *Attorney, Agent, or Firm* — Michael Best and Friedrich LLP(57) **CLAIM**

The ornamental design for a speaker, as shown and described.

DESCRIPTION

FIG. 1 is a front, top, right perspective view of a first embodiment of a speaker showing my new design;

FIG. 2 is a rear, top, left perspective view thereof;

FIG. 3 is a front elevational view thereof;

FIG. 4 is a rear elevational view thereof;

FIG. 5 is a left side elevational view thereof;

FIG. 6 is a right side elevational view thereof; and

FIG. 7 is a top plan view thereof; and,

FIG. 8 is a bottom plan view thereof.

The even-dash broken lines illustrating portions of the speaker form no part of the claimed design. The dot-dash broken lines defining boundaries of the claimed design from no part of the claimed design.

1 Claim, 8 Drawing Sheets(56)
